UNITED STATES PATENT OFFICE.

EMILE GÉRARD, OF LIMOGES, FRANCE.

DESIGN FOR A COVERED DISH.

SPECIFICATION forming part of Design No. 26,299, dated November 17, 1896.

Application filed October 7, 1896. Serial No. 608,182. Term of patent 7 years.

To all whom it may concern:

Be it known that I, EMILE GÉRARD, a citizen of France, residing at Limoges, in the Department of Haute-Vienne and Republic of France, have invented and produced a new and original Design for Dishes; and I do hereby declare the following to be a full, clear, and exact description of the same, reference being had to the accompanying drawings, forming a part thereof.

The principal feature of my design consists of a low covered dish ornamented as herewith described.

Figure 1 shows the cover, and Fig. 2 the body.

The cover and the body of the dish are divided into several sections formed by two rays that spring from the circumference of the cover and extend toward the center of the cover and from the upper edge of the body of the dish to the base of the same.

In Fig. 1 the handle *a* is scroll-like in shape, and where it joins the dish at *b* there

is a leaf-like ornamentation, and where it joins at *c* a scroll-like ornamentation. Surrounding these ornamentations is a simulated 25 rococo wreath *d*, irregular in design. Between the two rays *e e* and on either side of the same are shell-like and floral 30 ornamentations reaching from the circumference toward the center of the cover.

The body of the dish, Fig. 2, has the same rays and ornamentations as the cover with the exception that the simulated wreath of 35 roccoco-work passes around the base of the body of the dish.

What I claim is—

The design for a dish substantially as shown and described.

In testimony whereof I herewith affix my 40 signature in presence of two witnesses.

EMILE GÉRARD. [L. S.]
